STRAIN RELIEF FOR ELECTRICAL CONNECTORS

John S. Prifogle, Williamsburg, and Richard C. Vail, Richmond, Ind., assignors to Belden Corporation, a corporation of Illinois

Filed Sept. 8, 1966, Ser. No. 3,778

Term of patent 14 years

(Cl. D26—1)

FIGURE 1 is an elevation of a strain relief for electrical connectors showing our new design;

FIGURE 2 is an end elevation viewed along line 2—2 of FIGURE 1;

FIGURE 3 is an elevation of a modified embodiment of the strain relief shown in FIGURE 1.

The broken lines are shown for illustrative purposes only.

We claim:

The ornamental design for a strain relief for electrical connectors, as shown and described.
